Des. 214,443
Patented June 17, 1969

214,443

COMBINED CORNER CABINET AND LAVATORY

George A. Colonna, 7313 Shisler St.,
Philadelphia, Pa. 19111

Filed Mar. 29, 1968, Ser. No. 11,195

Term of patent 14 years

Int. Cl. D23—02

U.S. Cl. D23—59

Fig. 2.

Fig. 4.

Fig. 3.

The broken line representation of a corner and soffit in FIGURE 1 is for purposes of illustration only.

I claim:

The ornamental design for a combined corner cabinet and lavatory, substantially as shown and described.
